Primary Examiner — April Rivas*Assistant Examiner* — Justin A Johnson(74) *Attorney, Agent, or Firm* — Panitch Schwarze Belisario & Nadel LLP(57) **CLAIM**

The ornamental design for a medication mixing apparatus, as shown and described.

DESCRIPTION

FIG. 1 is a front perspective view of a medication mixing apparatus in accordance with my new design;

FIG. 2 is a left-side elevational view thereof;

FIG. 3 is a right-side elevational view hereof;

FIG. 4 is a front elevational view thereof;

FIG. 5 is a rear elevational view thereof;

FIG. 6 is a top plan view thereof; and,

FIG. 7 is a bottom plan view thereof.

The portions shown in broken lines are unclaimed environment, and form no part of the claimed design.

1 Claim, 7 Drawing Sheets# US D923,812 S
